HOLD-DOWN CLIP FOR ELECTRIC LIGHTING
FIXTURES

George Ernest Oremus, Buffalo, N. Y., assignor to
Markel Electric Products, Inc., Buffalo, N. Y., a
corporation of New York

Application October 28, 1936, Serial No. 108,045

3 Claims. (Cl. 240—73)

This invention relates to improvements in electric lighting fixture of the so-called wall bracket type and more particularly the invention is concerned with fixtures of the kind where-
5 in the arm which bears the lamp is formed with a channel to accommodate the wire which leads to the socket of the said lamp.

The principal object of the invention is an electric lighting fixture of the type generally described in which provision is made for holding the wire which is arranged in the channel of the arm of the fixture in such a position that it is concealed from view, this object contemplating the use of a clip which is so designed that it may 15 be employed in connection with standard fixtures.

A further object is to provide a clip which may be applied with facility and which will not impair the insulation of the wire.

The invention is illustrated in the accompanying drawing in which:

Figure 1 is a view partially in elevation and partially in section of a fixture embodying the features of the invention.

Figure 2 is an enlarged section taken along line 2—2 of Figure 1.

Figure 3 is a perspective view of the clip.

Figure 4 is a similar view illustrating the clip as it appears in Figure 1.

The fixture illustrated in Figure 1 is of the wall bracket type. It includes a socket 5 for a lamp 6, a diffuser 7 being suitably secured to the socket 5 and carrying a shade 8. The lamp thus provided is adapted to be mounted upon a suitable supporting surface by a bracket 9 which 30 comprises a plate 10 and an arm 11. The lower end of the arm 11 fits in a shallow recess 12 which is formed in the plate 10 and is secured therein by a screw 13. The latter passes through an opening 14 which is formed in an elevated portion 15 of the plate 10 and is screwed into a suitable opening formed in the arm 11. The 40 socket 5 is connected to power by a wire 16. The latter is arranged in a channel 17 which is formed in the arm 11, the said wire entering the channel through an opening 18 which is formed in the elevated portion 15 of the plate 10.

Means is provided for holding the wire 16 within the channel 17 so that it will remain concealed from view. The said means comprises a clip 19 which, at the outset, is of the shape shown in Figure 3. The clip may be of metal or any other suitable material. As illustrated, it includes a body portion 20 which is formed with holes 21 and 22 and a tongue 23.

During the assembling operations the body portion 20 of the clip is arranged in the recess 12 so that the holes 21 and 22 thereof register with the openings 14 and 18, respectively, formed in the plate 10. The arm 11 is then arranged in the recess 12 over the body portion of the clip 19 and the parts are secured together by the screw 13. Thereafter the wire 16 is passed through the openings 18 and 22, that portion of the wire between the plate 10 and the socket 5 being pushed down into the channel 17. The wire 16 is held in this position by the tongue 23 which is bent down upon it as best shown in Figure 1. The hole 22 is preferably of a greater diameter than the wire 16 and it is formed so as to provide weakened portions 24 (Figures 3 and 4), whereby as the tongue is forced downwardly upon the wire 16 in the manner described it will bend along a line which passes through the said portions. Owing to the size of the hole 22 and the elevation of the line along which the clip bends the wire 16 is not pinched. As a result of this and the relatively large contact area which is provided by the tongue 23 injury to the insulation is avoided.

From the foregoing it will be apparent that the clip can be readily applied to a standard fixture as the parts of the latter are assembled, the same fastening means which is employed to secure the arm 11 to the plate 10 being available 30 to secure the clip to the bracket. After the parts are assembled and the tongue 23 has been bent upon the wire 16 in the manner described the entire clip will be concealed from view. It will not, therefore, detract from the appearance of 35 the fixture.

I claim:

1. The combination with a fixture of the kind having a lamp which is carried by an arm, a socket for said lamp, a plate for mounting said arm upon a supporting surface, and fastening means for securing said arm to said plate, said arm being formed with a channel in which the wire leading to said socket is arranged, of a clip which is secured between said plate and arm by 40 said means, said clip having an opening through which said wire passes and being formed with a tongue which extends in the direction of the length of said wire and which is adapted to engage said wire and hold it in said channel.

2. The combination with a fixture of the kind having a lamp which is carried by an angularly extending arm, a socket for said lamp which is carried by one end of said arm, a plate for mounting said arm upon a supporting surface,

and fastening means for securing the opposite end of said arm to said plate, said arm being formed with a channel in which the wire leading to said socket is arranged, of a clip which is secured between said plate and arm by said fastening means, said clip having one opening through which said fastening means passes and a second opening through which said wire passes and being formed with a tongue which extends 5 in the direction of the length of said wire and which is pressed against said wire to hold it in said channel, said second opening providing weakened portions along which said clip is bent as said tongue is pressed against said wire for 10 the purpose described.

15 3. The combination with a fixture of the kind

having a lamp which is carried by an arm, a socket for said lamp, a plate for mounting said arm upon a supporting surface, said plate being formed with an opening and fastening means for securing said arm to said plate, said arm being formed with a channel in which the wire leading to said socket is arranged, of a clip which is secured between said plate and arm, said clip having an opening which registers with the opening in said plate, said wire passing through 10 both of said openings, said clip being formed with a tongue which extends in the direction of the length of said wire and which engages said wire to hold it in said channel.

5
